CLAIM

The ornamental design for a wearable electronic device, as shown and described.

DESCRIPTION

FIG. 1 is a front perspective view of the first embodiment of a wearable electronic device, showing our new design; FIG. 2 is a front view thereof; FIG. 3 is a rear view thereof; FIG. 4 is a side view thereof; FIG. 5 is another side view thereof; FIG. 6 is a top view thereof; FIG. 7 is a bottom view thereof; FIG. 8 is a rear perspective view thereof; FIG. 9 is a front perspective view of the second embodiment of a wearable electronic device, showing our new design; FIG. 10 is a front view thereof; FIG. 11 is a rear view thereof; FIG. 12 is a side view thereof; FIG. 13 is another side view thereof; FIG. 14 is a top view thereof; FIG. 15 is a bottom view thereof; and, FIG. 16 is a rear perspective view thereof.

The broken lines depicting portions of the wearable electronic device form no part of the claimed design.
